CLAIM

The ornamental design for a vehicle light as shown and described.

DESCRIPTION

FIG. 1 is a front, right perspective view of the claimed design for a vehicle light;

FIG. 2 is a front, left perspective view thereof;

FIG. 3 is a front view thereof;

FIG. 4 is a right side view thereof;

FIG. 5 is a left side view thereof; and,

FIG. 6 is a top view thereof.

The broken lines depicting the remainder of the vehicle light form no part of the claimed design. The oblique line shading represents that the surfaces have a transparent, translucent, or reflective appearance.
